UNITED STATES PATENT OFFICE

2,451,091

KEY RING

Keith Whitaker Johnson, Arlington County, Va.

Application March 18, 1946, Serial No. 655,093

20 Claims. (Cl. 70—456)

1

This invention relates to key-rings such as are commonly employed to hold a bunch of keys for greater safety and convenience in the carrying and handling thereof. More specifically, this invention relates to key-rings having means by which keys may be applied to and withdrawn from the key-ring.

One of the objects of this invention is to provide a key-ring wherein the keys may be applied and withdrawn from the key-ring with increased ease and facility.

Another object of this invention is to provide a key-ring wherein the keys are secure against accidental withdrawal.

Another object of this invention is to provide a key-ring with means of identification or advertisement in connection with an opening device.

The prior art includes United States Patent No. 765,754 (issued to Siersdorfer, July 26, 1904), in which is disclosed a circular key-ring of elastic material openable by means of a cam-faced opening plate which may be forced between opposite inner points on the ring on opposite sides of the meeting ends of the ring in order to separate the latter and thus permit the removal or application of a key. Such opening plate can also serve to carry an identification or advertisement. Such prior opening device lacks a positive means of assuring that, when the opening device is being forced into operative position, the opening device will not move beyond such operative position and become again in loose or inoperative position on the key-ring. If such opening device is not pressed far enough between the opposite inner points of the ring, the ring will not open sufficiently. If the opening device is pressed too far, the ring will snap closed before any key can be removed or applied to the ring. Such prior device may also be uncomfortable to the user, since it requires the user to press against the relatively sharp edge of the opening plate, and insufficient means are provided to either decrease or overcome operational friction.

The present invention overcomes these disadvantages and discloses a more practical cam-operated key-ring. In the present invention, a stop is provided to prevent the opening device from being forced beyond the operative position. The stop also provides an operative lever extending longitudinally of the opening device and appreciably beyond the cam-surface, providing greater operative leverage. Such operative lever is also readily adapted to present or carry a flat surface, which is more suitable to

2

receive operative pressure than is a relatively sharp edge. In some forms of the present invention, the use of a wheel for a cam serves to decrease operational friction.

5 The present invention essentially consists in the combination, with a resilient ring divided at one point and having its meeting ends normally pressed together by the resiliency of the material, of an opening device carried on the ring and having a cam and at one end of said cam a stop, which opening device may be forced between opposite inner points on the ring on opposite sides of the meeting ends thereof to separate the latter, the said stop facilitating the moving of the operative device precisely into full operative position on the ring, in which position the meeting ends of the ring are at maximum separation, yet preventing the opening device from being forced beyond the operative position, 10 thereby permitting the removal or application of a key. The stop may serve also as an operational lever to facilitate pressing the opening device into and out of operative position. The operative lever may be provided with a flat surface to receive 15 operational pressure. The cam may be either a cam-surface of the opening device, or a wheel positioned on the opening device so as to serve as a cam.

The invention is illustratively exemplified in 20 the accompanying drawings, in which:

Figure 1 is a perspective view showing one embodiment of the key-ring with the opening device in idle or inoperative position;

Figure 2 is a perspective view showing the 25 same embodiment of the key-ring with the opening device in operative position, wherein the ring is opened for the application or removal of a key;

Figure 3 is a plan view of the opening device 30 detached;

Figure 4 is a lower edge view of the opening device shown in Figure 3;

Figure 5 is a plan view of a modification of 35 the opening device shown in Figures 1, 2, 3 and 4;

Figure 6 is a lower edge view of the opening device shown in Figure 5;

Figure 7 is a plan view of another embodiment 40 of the opening device detached;

Figure 8 is a lower edge view of the opening 45 device shown in Figure 7;

Figure 9 is a plan view of a modification of 50 the opening device shown in Figures 7 and 8; and

Figure 10 is a lower edge view of the opening device shown in Figure 9.

Referring to Figures 1, 2, 3 and 4, the ring 1 is

made of any suitable material possessing the necessary strength and resiliency, for example, a good grade of steel. The ring is divided at a point therein, preferably with the meeting ends 2 and 3 being provided with serrated teeth adapted to inter-mesh when the meeting ends of the ring come together, thereby assuring against accidental removal of keys when the ring is closed. Alternatively, one of the meeting ends may be provided with a recess or socket while the other meeting end is provided with a tapering point. Or, other shapes of meeting ends may be used.

Two keys 13 and 14 are shown mounted on the ring in the usual manner.

The opening device consists of a plate or strip 4 of metal or other suitable material, with a hole 5 in one end for mounting the opening device on the ring, while the opposite end has a cam-wheel 6 mounted thereon, and an extension 8. The rim of wheel 6 extends from below one longitudinal edge of the opening device and across a portion of the width thereof and protrudes also beyond the end thereof except for that portion thereof forming the extension 8 and flat surface 9. On extension 8 and adjoining said wheel 6 is a stopping surface 7. Extension 8 also serves as an operative lever and carries the flat surface 9 at right angles to the plane of the plate. The flat surface 9 centers over wheel 6, and is adapted to receive operative pressure upon the extension 8. The plate 4 is of such length that, when the opening device is being turned about that portion of the ring adjacent hole 5, the opposite end of the opening device may be brought into operative contact with that portion of the ring opposite from hole 5. The portion of the ring opposite hole 5 will first engage that part of wheel 6 which is at position 10, whereupon a light pressure applied to the flat surface 9 readily forces wheel 6 through the ring, so that that portion of wheel 6 which is at position 11 engages the ring, whereby the opposite sides of the ring are separated and held apart. In performing this operation, surface 9 and that part of the ring opposite hole 5 may be squeezed together by the thumb and fingers of one hand. The stopping surface 7 stops the motion of the opening device through the ring at a point at which the meeting ends of the ring are held sufficiently apart for the removal or application of a key. The stopping surface 7 also prevents the motion of the opening device too far through the ring, whereby the meeting ends of the ring would be no longer held apart.

When the meeting ends of the ring have been placed in separated position, as described above, and as shown in Figure 2, then a key, such as 13, lying on that side of the opening device on which the meeting ends of the ring have been opened may be readily removed. Similarly, keys may be applied to the ring. It may be desired that keys such as 14 should not be removed, in which case such keys are left on the other side of the opening device, as shown in Figure 2. As soon as the desired keys have been applied or withdrawn through the opening between the ends 2 and 3, the opening device may be quickly and easily pushed into a disengaged position, whereupon the ends 2 and 3 of the ring will snap together.

In Figures 5 and 6, parts corresponding to those hereinbefore described have been designated by numerals already used, with the suffix a.

Figures 5 and 6 illustrate a modification of the hereinbefore described opening device. In Figures 5 and 6, the cam-wheel 6a is mounted between two parallel plates 4a, which are joined at

each end. Each plate has an aperture 5a at the opposite end from the wheel 6a. The two top edges 8a of the extension 8a of the plates 4a provide a two-fold edge surface to receive operative pressure. This modification provides a steadier mounting for the wheel. This modification presents no projections and so would cause less wear to the pocket of the user.

In Figures 7 and 8, parts corresponding to those hereinbefore described have been designated by numerals already used, with the suffix b.

Figures 7 and 8 illustrate another embodiment of the opening device, in which the cam-wheel is replaced by a cam-surface 10b and a straight surface 11b, whereby, respectively, the ends of the ring may be separated and may be maintained apart. The stopping surface 7b serves to stop the motion of the opening device relative to the ring at the point at which maximum separation of the ends of the ring has been achieved. The flat surface 9b, for receiving operative pressure, is provided as a result of a 90-degree twist in extension 8b; this method of providing a flat surface assures the proper alignment of the flat surface with the cam surface 10b and straight surface 11b. While the embodiment shown in Figures 7 and 8 lacks a wheel to decrease operational friction, this embodiment is more compact, simpler and more economical to make than are embodiments having a cam-wheel.

In Figures 9 and 10, parts corresponding to those hereinbefore described have been designated by numerals already used, with the suffix c.

Figures 9 and 10 illustrate a modification of the opening device illustrated in Figures 7 and 8. In Figures 9 and 10, the cam-surface 10c, straight surface 11c and stopping surface 7c, are all surfaces of a notch in the plate 4c. The plate extends longitudinally beyond the notch to provide an operative lever portion 8c with a surface 9c to receive operative pressure. The pendant portion 12c beneath lever portion 8c is what chiefly distinguishes this modification from that in Figures 7 and 8. The pendant portion 12c serves to provide a blunt end to the opening device; yet neither the stopping surface 7c nor the operative lever portion 8c, with surface 9c, have to be omitted to provide a blunt end to the opening device. By contrast, in Figures 7 and 8, the operative lever 8b provides a relatively more pointed end. The blunter end shown in Figures 9 and 10 will cause less wear upon the pocket of the user. The modification shown in Figures 9 and 10 is also particularly suitable for carrying advertising or an identification, since a larger area is available, namely, space on both sides of the cam-notch. In the other forms of the invention, space was available on only one side of the cam.

In any of the forms of the opening device, the surface which receives operative pressure may be of any of the hereinbefore disclosed types or of other suitable types, flat or otherwise.

The side of any of the hereinbefore disclosed embodiments may carry advertising, or an identification, or other ornamentation.

The ring and the opening device may either or both be made of an alloy containing precious metals, or a plating of precious metals may be applied, or other suitable materials may be employed.

While the present invention has been described by reference to specified forms thereof, it will be understood that many changes and modifications may be made without departing from the spirit of the invention.

What I claim is:

1. The combination with a resilient key-ring, of an opening member carried thereby having a cam adapted to force apart the opposite sides of the ring, whereby the meeting ends of the ring may be separated, and a stop adjacent to said cam to prevent the movement of the opening member relative to the ring in one direction beyond the position at which the meeting ends of the ring are maintained separated.

2. The combination with a resilient key-ring, of an opening member carried thereby having a cam adapted to force apart the opposite sides of the ring, whereby the meeting ends of the ring may be separated, and a stop adjacent to said cam to prevent the movement of the opening member relative to the ring in one direction beyond the position at which the meeting ends of the ring are maintained separated, said stop extending longitudinally of the opening member to provide an operative lever.

3. The combination with a resilient key-ring, of an opening member carried thereby having a cam adapted to force apart the opposite sides of the ring, whereby the meeting ends of the ring may be separated, and a stop adjacent to said cam to prevent the movement of the opening member relative to the ring in one direction beyond the position at which the meeting ends of the ring are maintained separated, said stop extending longitudinally of the opening member to provide an operative lever and having a flat surface adapted to receive operative pressure.

4. The combination with a resilient key-ring, of an opening member carried thereby having a notch, one surface of said notch having a cam-surface adapted to force apart the opposite sides of the ring, whereby the meeting ends of the ring may be separated, another surface of said notch being adapted to serve as a stop to prevent the movement of the opening member relative to the ring in one direction beyond the position at which the meeting ends of the ring are maintained separated.

5. The combination with a resilient key-ring, of an opening member carried thereby, said opening member having a wheel mounted thereon adapted to cam apart the opposite sides of the ring, whereby the meeting ends of the ring may be separated, and a stop adjacent to said wheel to prevent the movement of the opening member relative to the ring in one direction beyond the position at which the meeting ends of the ring are maintained separated.

6. The combination with a resilient key-ring, of an opening member carried thereby, said opening member having a wheel mounted thereon adapted to cam apart the opposite sides of the ring, whereby the meeting ends of the ring may be separated, and a stop adjacent to said wheel to prevent the movement of the opening member relative to the ring in one direction beyond the position at which the meeting ends of the ring are maintained separated, said stop extending longitudinally of the opening member to provide an operative lever.

7. The combination with a resilient key-ring, of an opening member carried thereby, said opening member having a wheel mounted thereon adapted to cam apart the opposite sides of the ring, whereby the meeting ends of the ring may be separated, and a stop adjacent to said wheel to prevent the movement of the opening member relative to the ring in one direction beyond the position at which the meeting ends of the ring

are maintained separated, said stop extending longitudinally of the opening member to provide an operative lever and having a flat surface adapted to receive operative pressure.

5 8. The combination with a resilient key-ring, of an opening member apertured at one end to receive the ring and provided at its opposite end with a wheel mounted thereon, said wheel being adapted to cam apart the opposite sides of the ring, whereby the meeting ends of the ring may be separated, and a stop adjacent to said wheel to prevent the movement of the opening member relative to the ring in one direction beyond the position at which the meeting ends of the ring are maintained separated.

10 9. The combination with a resilient key-ring, of an opening member apertured at one end to receive the ring and provided at its opposite end with a wheel mounted thereon, said wheel being, adapted to cam apart the opposite sides of the ring, whereby the meeting ends of the ring may be separated, and a stop adjacent to said wheel to prevent the movement of the opening member relative to the ring in one direction beyond the position at which the meeting ends of the ring are maintained separated, said stop extending longitudinally of the opening member to provide an operative lever.

15 10. The combination with a circular key-ring, 30 of resilient material, of an opening member comprising a plate mounted at one end on the ring, a wheel mounted at the opposite end of the plate, said wheel being adapted to cam apart the opposite sides of the ring, whereby the meeting ends of the ring may be separated, and a stop provided upon said plate adjacent to said wheel to prevent the movement of the opening member relative to the ring in one direction beyond the position at which the meeting ends of the ring are maintained separated.

20 11. The combination with a circular key-ring, 35 of resilient material, of an opening member comprising a plate mounted at one end on the ring, a wheel mounted at the opposite end of the plate, said wheel being adapted to cam apart the opposite sides of the ring, whereby the meeting ends of the ring may be separated, and a stop provided upon said plate adjacent to said wheel to prevent the movement of the opening member relative to the ring in one direction beyond the position at which the meeting ends of the ring are maintained separated.

25 12. The combination with a resilient key-ring, 40 of an opening member apertured at one end to receive the ring, and provided on its opposite end with a cam-surface whereby the opposite sides and meeting ends of the ring may be forced apart, and a stop adjacent to one end of the cam-surface to prevent movement of the opening member relative to the ring in one direction beyond the position at which the meeting ends of the ring are maintained separated.

30 13. The combination with a resilient key-ring, 45 of an opening member apertured at one end to receive the ring, and provided on its opposite end with a cam-surface whereby the opposite sides and meeting ends of the ring may be forced apart, and a stop adjacent to one end of the cam-surface to prevent movement of the opening member relative to the ring in one direction beyond the position at which the meeting ends of the ring are maintained separated, said stop

extending longitudinally of the opening member to provide an operative lever.

14. The combination with a resilient key-ring, of a plate apertured at one end to receive the ring and provided on its opposite end with a cam-surface, whereby the opposite sides and meeting ends of the ring may be forced apart, adjoining said cam-surface a straight surface at right angles to the longitudinal axis of the plate, whereby the forced apart ends of the ring may be maintained separated, and adjoining said straight surface a stop to prevent movement of the plate relative to the ring in one direction beyond the position at which the ends of the ring are maintained separated.

15. The combination with a resilient key-ring, of a plate apertured at one end to receive the ring and provided on its opposite end with a cam-surface, whereby the opposite sides and meeting ends of the ring may be forced apart, adjoining said cam-surface a straight surface at right angles to the longitudinal axis of the plate, whereby the forced apart ends of the ring may be maintained separated, and adjoining said straight surface a stop to prevent movement of the plate relative to the ring in one direction beyond the position at which the ends of the ring are maintained separated, said stop extending longitudinally beyond the plate to provide an operative lever.

16. The combination with a circular key-ring of resilient material, of an opening member in the form of a plate of slightly greater length than the diameter of the ring, said plate being mounted on the ring at one end and at its opposite end having a cam-face extending inwardly from a longitudinal edge of the plate, whereby the opposite sides and meeting ends of the ring may be forced apart, said cam-face terminating in a straight face at right angles to the longitudinal axis of the plate, whereby the meeting ends of the ring may be held apart, said straight face terminating in a stop, whereby is prevented any motion of the opening member relative to the ring in one direction beyond the position at which the meeting ends of the ring are held apart.

17. The combination with a circular key-ring of resilient material, of an opening member in the form of a plate of slightly greater length than the diameter of the ring, said plate being mounted on the ring at one end and at its opposite end having a cam-face extending inwardly from a longitudinal edge of the plate, whereby the opposite sides and meeting ends of the ring may be forced apart, said cam-face terminating in a straight face at right angles to the longitudinal axis of the plate, whereby the meeting ends of the ring may be held apart, said straight face terminating in a stop whereby is prevented any

5 motion of the opening member relative to the ring in one direction beyond the position at which the meeting ends of the ring are held apart, said stop extending longitudinally beyond the plate to provide an operative lever.

18. The combination with a resilient key-ring, of an opening member apertured at one end to receive the ring, and provided with a notch, one surface of said notch being adapted to serve as 10 a cam to force apart the opposite sides of the ring, whereby the meeting ends of the ring may be separated, another surface of said notch being adapted to serve as a stop to prevent the movement of the opening member relative to the ring in one direction beyond the position at which the meeting ends of the ring are maintained separated.

19. The combination with a resilient key-ring, of an opening member mounted on the ring at one end, and provided with a notch having a cam-surface extending inwardly from a longitudinal edge of the opening member and adapted to force apart the opposite sides of the ring, whereby the meeting ends of the ring may be separated, 20 adjoining said cam-surface a straight surface at right angles to the longitudinal axis of the opening member, the straight surface being adapted to maintain the meeting ends of the ring in separated position, and adjoining said straight surface a stop-surface adapted to prevent the movement of the opening member relative to the ring in one direction beyond the position at which the meeting ends of the ring are maintained separated.

25 30 35 40 45 50 55 20. The combination with a circular key-ring of resilient material, of an opening member in the form of a plate, said plate having an aperture to receive the ring and a notch spaced apart from the aperture by substantially the length of the diameter of the ring, said notch having a cam-face extending inwardly from the longitudinal edge of the opening member, said cam-face terminating in a straight face lying transversely of the intermediate longitudinal portion of the plate, said straight face terminating in a stop-face adapted to prevent the movement of the opening member relative to the ring in one direction beyond the position at which the meeting ends of the ring are maintained separated.
